UNITED STATES PATENT OFFICE.

ADOLPH A. THOMAS, OF NEW YORK, N. Y.

SOUND AMPLIFIER.

Application filed November 16, 1922. Serial No. 601,237.

To all whom it may concern:

Be it known that I, ADOLPH A. THOMAS, a citizen of the United States, and a resident of the city of New York, county and State of New York, have invented new and useful Improvements in Sound Amplifiers, of which the following is a specification.

My invention relates to acoustic devices for amplifying sounds produced by vibratory diaphragms, as in phonographs, telephone receivers, radio receiving apparatus, and the like. The object of my invention is to produce a sound-amplifier giving improved tone effects and capable of adjustment to control the quality and volume of the amplified sounds.

The most common form of sound-amplifier in use is a horn or megaphone. In fact, this type of amplifier is employed almost universally in phonographs and radio loudspeakers. Everybody familiar with amplifying horns knows that they possess certain inherent objections in reference to tone quality. These objections are best described by saying that horns give out sounds of an unnatural "horny" quality with consequent loss in clearness. In an endeavor to reduce this defect as much as possible, manufacturers have put in the market a great variety of shapes and sizes of horns constructed of various kinds of materials.

It is known that metal horns produce hard penetrating sounds, which may become particularly offensive in the higher tones, especially when the vibrations of the diaphragm are of considerable amplitude. This is a common experience. So that, while the tones of a metal horn have volume, they are defective in quality and distinctness.

On the other hand, horns of non-metallic material—such as wood, fiber, compressed paper, composition, and the like—produce sounds of considerably less volume than corresponding horns of metal. While these softer tones may be preferable to the loud sounds of a metal horn when the vibrations of the diaphragm are strong, there is the objection that a non-metallic horn has little carrying power when the diaphragm vibrations are weak.

Attempts have heretofore been made to damp or weaken the action of phonograph horns by choking back the sounds. This has been done either by partially closing the mouth of the horn or by using a damper in the throat of the horn. In either case, the

resultant tones are decidedly muffled or "choky" and lack the required clearness.

The foregoing and other objections and disadvantages of prior sound-amplifiers are effectively overcome by the new amplifying device of my invention. Broadly stated, the fundamental idea of my invention involves the use of a plurality of sound chambers constructed to produce different tone effects, so that the resultant tones are a blending of the sounds produced by the individual amplifying chambers. By combining a relatively resonant chamber with a relatively mellow chamber, I secure a resultant tone effect which embodies the acoustic advantages of both chambers. I also provide means for controlling the resultant reproduction of the amplifier by varying the acoustic effect of one or more of the sound chambers.

One of the simplest forms of my invention comprises a metal horn surrounded by non-metallic walls (say, of wood) so arranged as to form a conical or pyramidal sound chamber around the horn. The chamber and the horn are open to the free air at their outer ends. The horn is at its inner end connected with a source of sound, which may be, for instance, a phonograph sound-box, a telephone receiver, or the diaphragm of a radio loudspeaker. By means of properly arranged openings, the sound waves enter both amplifying chambers. The resultant tone effect of the two chambers is a blending of the sharp resonant tones of the inner metal horn with the mellow tones of the outer wooden chamber. In other words, I may say that the resonant tones of the horn are mellowed by the tones of the surrounding outer chamber, and the mellow tones of this chamber are strengthened by the resonant tones of the horn. My new amplifier thus combines volume with quality.

To vary the resultant tone effect of the instrument as desired, I provide means for readily controlling the relative proportion of sound waves issuing out of each chamber. For this purpose I employ a valve or shutter arrangement by means of which the travel of sound waves through each chamber is regulated. Assuming, as in the example above cited, that we have an inner metal chamber and an outer wooden chamber, the more sound waves we send through the metal chamber, the stronger becomes

the final reproduction. Conversely, the greater the proportion of sound waves that pass through the outer wooden chamber, the more mellow are the resultant tones. This 5 control of the sound-amplifying action of my new apparatus is especially useful in phonographs and radio loudspeakers.

Another feature of my invention resides in the construction whereby the inner horn 10 or chamber is provided with a sound-conveying tube which is bent back over the horn, thereby producing an amplifier of compact dimensions and yet providing a sound passage of increased length, with a resultant in- 15 crease in the volume of tone production.

In order to explain my invention fully and clearly, I shall describe in detail the illustrative embodiments shown in the accompanying drawings, in which—

20 Figure 1 is a longitudinal cross-section of a box or cabinet containing my new amplifier;

Fig. 2 is a front view of the box shown in Fig. 1;

25 Fig. 3 is a view similar to Fig. 2, with the front grille or frame removed;

Fig. 4 is a detached view of the casting to which the inner ends of the sound chambers are connected;

30 Fig. 5 is an enlarged cross-sectional view of the casting;

Fig. 6 shows my new amplifier attached to a radio loudspeaker, the amplifier and a portion of the loudspeaker being shown in cross- 35 section;

Fig. 7 is a cross-sectional view of a phonograph provided with the amplifier of my invention;

Fig. 8 is a view in longitudinal cross-section 40 showing a modified form of amplifier, portions of the horns being broken away;

Fig. 9 is a view taken approximately on line 9—9 of Fig. 8;

Fig. 10 shows a full view, on a smaller 45 scale, of the amplifier shown partially in Fig. 8, the walls of the horns being broken away for clearness;

Fig. 11 is a cross-sectional view showing a modified form of control valve for the 50 sound chambers;

Fig. 12 is a cross-section approximately on line 12—12 of Fig. 11; and

Fig. 13 is a cross-section approximately on line 13—13 of Fig. 11, except that the 55 valve is shown turned to close the outer horn.

Referring first to Figs. 1 to 5, inclusive, there is a box or cabinet A of suitable dimensions and material. Within the box is a 60 casting indicated as a whole by C, which may conveniently be cast of metal or molded out of some suitable composition material. When I speak of the part C as a casting, I use the term as a convenience in a broad 65 sense, irrespective of the process of which

the part is made or the material of which it is composed. Casting C is supported between the arms 1 of a standard 2, which is fastened to the bottom of the box by screws or bolts 3. The arms 1 of the support 2 are 70 preferably provided with slots 3' through which pass screws 4 into the casting. The slots 3' permit adjustment of the height of the casting. Any suitable supporting means for holding the casting C in proper position 75 may be used. Casting C is formed with a tubular hub having a front section 5 and rear section 6, this hub providing a sound passage 7. Hub section 5 is surrounded by an outwardly diverging flange 8. In the 80 drawings, this flange is shown rectangular, because it has been assumed that the walls of the outer sound chamber secured to this flange are four in number, as will presently be explained. The shape of the flange 8 will 85 depend on the shape of the inner end of the sound chamber to be attached to it.

On the hub section 5 of casting C is mounted the inner end of a horn, indicated as a whole by H. The outer surface of hub 90 section 5 may be slightly tapering, so as to make it easy to slip the horn on the casting in a tight fit, as indicated in Figs. 1 and 5.

Horn H is surrounded by a sound chamber which, in this instance, is formed by 95 four walls 9 secured at their inner ends to flange 8 of casting C. Suitable fastening devices, such as screws or bolts 10, pass through holes 11 in flange 8 into the walls 9. The chamber formed by walls 9 is indicated as a whole by R.

The horn or inner chamber H is preferably constructed of a material adapted to give a strong resonant reproduction—such as brass, aluminum, German silver, or other 100 material suitable for this purpose. The walls 9 of the outer sound chamber are preferably of non-metallic material adapted to give a mellow reproduction—such as wood, fiber or a suitable composition. If wood is 110 used, maple gives particularly good results.

As seen in Figs. 1 and 3, horn H is provided with openings 12 for permitting the passage of sound waves laterally into the surrounding outer chamber R. This lateral 115 expansion of the sound waves from the inner to the outer chamber, before reaching the air, improves the quality of the final tone reproduction. The size, arrangement and number of openings 12 may be varied, and will depend upon the size, shape and materials of the sound chambers and also upon the particular acoustic effects desired.

Above the sound chambers in the box or cabinet A is a sound-conveying tube or arm 13, which is preferably tapering, as shown in Fig. 1. The outer smaller end 14 of this arm terminates at the top of the box and is adapted to receive a suitable telephone receiver, indicated as a whole by T. This re- 120 125

ceiver may be of any approved type or construction, such as are used in radio reception, for instance. There are many sizes and styles of such receivers on the market.

5 The inner end of tone arm 13 is connected with the sound passage 7 of casting C by a substantially U-shaped tube 15. As shown in Fig. 1, the lower end of the U-shaped tube 15 is fitted into hub section 6 of casting C.

10 Sound tubes 13 and 15 are preferably of metal and, by arranging them as shown in Fig. 1, I secure a sound passage of great length between the telephone receiver T and the inner end of horn H, the effect being

15 that of a horn having a portion turned back upon itself. This increased length of horn increases its amplifying power and yet produces a compact construction, a feature particularly desirable in radio-receiving apparatus.

The front of box A is open and over this opening is fastened a frame or grille F, as shown in Figs. 1 and 2. Grille F may be stamped or cut out of metallic or non-metallic material, or it may be molded out of a suitable composition substance. This grille, which is secured to the box by any suitable means, such as screws 16, is provided with a central ring 17 adapted to fit over the mouth 30 of horn H, as shown in Figs. 1 and 2. Within the ring 17 is a disk 18 having openings 19, of which there are four in number in the present instance. On disk 18 is supported a rotary disk 20, which has openings 21 similar in shape and arrangement to openings 19. The rotary disk 20 is held in place by a spindle 22 provided on the outside with a knob 23. By turning knob 23, the disk 20 may be moved to cover or uncover the openings 19. In other words, the openings 19 and the disk 20 with its openings 21 constitute a valve or shutter for controlling the mouth of horn H.

It is clear that when the disk 20 is in 45 fully closed position, all the sound waves entering the horn are compelled to pass through the lateral openings 12 into the outer chamber R, whence they issue into the free air. As seen from Fig. 2, the grille F leaves the mouth of chamber R practically 50 unobstructed, there being only the thin connecting strips 24, which support the ring 17. If the walls 9 are of wood or other suitable 55 non-metallic material, the closing of valve disk 20 results in a mellow reproduction of tones passing through the amplifier. By opening valve disk 20 partially, the sound waves entering the horn pass into the outer air partly through the horn and partly 60 through chamber R, thus giving a stronger reproduction than when the disk 20 is closed. The more we uncover the horn openings 19, the more sound waves travel directly through and out of the horn. The 65 greater the proportion of sound waves issu-

ing out of the resonant horn H, the stronger and more resonant will be the final or resultant tone effect of the instrument. In this way, by blending the resonant tones of horn H with the mellow tones of chamber 70 R, we secure a tone reproduction which combines the advantage of volume of the inner resonant chamber with the advantage of mellow ness of the outer chamber. The resultant tonal effect may be varied by 75 changing the proportion of sound waves passing through each chamber.

In Fig. 6, I have shown my new combination of sound chambers attached in an upright position to a radio loudspeaker, indicated as a whole by L. It will not be necessary to repeat the details of construction and assemblage of the parts shown in Fig. 6, since they are similar to those shown in Fig. 1. It will be sufficient to say that in 80 Fig. 6 I have employed the same reference characters as in Fig. 1 to indicate corresponding parts, except that a prime mark is used with the characters for the sake of distinction. I may point out that in Fig. 6 the 85 wall or walls 9' of the outer sound chamber R' are substantially conical in cross-section instead of rectangular. Also, in Fig. 6, the casting C' has an extension 6' fitting directly into the sound passage or tube 25 of loudspeaker L. The operation and control of the amplifier shown in Fig. 6 are the same as those of the construction previously described.

In Fig. 7, I have shown my invention embodied in a phonograph. Practically the only difference between the constructions shown in Figs. 1 and 7 is that in Fig. 7 there is a casting C² which has a tubular extension 26 for connecting the horns or sound chambers R² and H² with the usual tone arm 27. Casting C² may be secured to the underside of motor board 28 by screws or bolts 29. Otherwise, what has been said about Fig. 1 applies fully to Fig. 7. The 100 advantages of my invention in a phonograph for controlling the reproduction are obvious. For instance, if the operator desires a mellow reproduction of a loud record, he need only turn the valve disk 20 to 105 close the mouth of the horn either completely or part way. On the other hand, in the case of a soft record, the reproduction is strengthened by opening the horn and thereby securing the advantage of its resonance in combination of the softer quality of the outer chamber.

Instead of using a valve or shutter to control the mouth of the inner horn, I may mount a conical valve on grille F to fit 115 closely against the horn and control the openings 12. As this modification is easily understood, I need not illustrate and describe it in detail, particularly since I do not claim it specifically. I mention it mere- 120 125 130

ly as one of the possible variations of my controlling valve.

In Figs. 8, 9 and 10 I have shown an amplifier embodying a modified form of tone-controlling device. A casting 30 is provided with a flange 31 to which is secured the inner end of an outer horn 32 by means of screws 33 or otherwise. Casting 30 is formed with a disk 34 and a tubular hub 35 which projects forwardly. The disk 34 has sound passages 36 and the hub 35 is at its inner end provided with sound passages 37. A horn 38 is mounted at its inner end on the hub 35 of casting 30, and is thus surrounded by the outer horn 32. The sound passages 36 lead into outer horn 32 and the sound passages 37 lead into the inner horn 38. The relative shapes and sizes of horns 32 and 38 are such that the sound space or chamber S between the two horns is of sufficient area to permit the free passage of sound waves.

To the casting 30 is secured a suitable extension 39 by means of which the inner chamber 40 of the casting is connected to a source of sound, which may be the vibratory diaphragm of a telephone receiver, or a phonograph sound box, or a radio loudspeaker.

I will now describe the means by which the passage of sound waves into horns 32 and 38 is readily controlled to produce different tone effects. Within the chamber 40 of casting 30 is mounted a valve, indicated as a whole by V. This valve consists of a disk 41 and a tubular extension 42. Valve disk 41 has openings 43 similar in size and arrangement to the passages 36. In Fig. 9, the disk 41 is in position to cover the passages 36 completely, which are therefore indicated in dotted lines. The cylindrical valve portion 42 is at its inner end provided with openings 44, which are substantially similar in size and arrangement to the sound passages 37. In Figs. 8 and 9, the valve openings 44 are shown in register with the sound passages 37, so that all of the sound waves entering chamber 40 pass into the inner horn 38. The controlling valve V is operated from the outside by any suitable means, such as a handle or lever 45, which projects through a slot 46 in the casting. If desired, pins or screws 47, or other means, may be used for positively holding the valve V against axial movement, although the lever 45 will probably be sufficient for that purpose.

Let us suppose that the inner horn 38 is constructed of a material adapted to give a resonant reproduction, and that the outer horn 32 is of a material which gives a relatively softer or more mellow reproduction. After the handle 45 is moved into the position shown in Figs. 8, 9 and 10 to close the sound passages 36 completely and to open fully the sound passages 37, all the sound

waves entering the amplifier pass through the resonant horn 38 and we get a correspondingly loud and sharp reproduction. In Fig. 10 this position of the controlling valve is indicated as the "loud" position. By moving the handle 45 half-way to the right (as viewed in Fig. 9), the sound passages 36 and 37 are approximately half-way open and the sound waves entering the amplifier pass into the free air partly through the mellow outer horn 32 and partly through the resonant inner horn 38. The resultant tone effect is a blending of the acoustic action of the two horns and gives a more mellow reproduction than horn 38 alone would give, and a more resonant reproduction than could be obtained with horn 38 alone. By moving the handle 45 to the extreme right position (as viewed in Fig. 9), the sound passages 37 are entirely closed and the sound passages 36 are open in full, so that all the sound passes through the outer horn 32 into the free air. This produces a still more mellow tone effect. It is clear that by adjusting the valve handle 45 in different intermediate positions, different tone effects will be produced.

Figs. 11, 12 and 13 show a construction similar to Figs. 8, 9 and 10, except that the controlling valve is slightly different in form, although it is precisely the same in operation as the previously described valve V. Referring in detail to the last three figures, we have a suitable casting 48 carrying an outer horn 49 and an inner horn 50, which are secured to the casting in the same way as the horns previously referred to. One of these horns (say, for example, the outer horn 49) is constructed of a material adapted to give a comparatively mellow reproduction, and the other horn (in that case horn 50) is of a material which gives a more resonant reproduction. The casting 48 has a cylindrical hub 51 provided with a set of sound passages 52 and another set of sound passages 53. As seen from Fig. 11, the sound passages 52 lead into the outer horn 49 and the sound passages 53 communicate with the inner horn 50. Within the hub 51 is mounted a cylindrical valve V' having a set of openings 54 and another set of openings 55. Valve openings 54 are adapted to control the sound passages 52, and valve openings 55 are arranged to control the sound passages 53. The valve V' is controlled from the outside by any suitable means, such as a handle 56, which projects through a slot 57 in the casting 48. In Figs. 11 and 12, the valve V' is in position to close the sound openings 53 and open the sound openings 52, so that all the sound waves pass through the outer horn 49, which we have assumed to be the more mellow sound chamber. The valve is thus in what we may call the "soft" position, as indicated in Fig. 12.

By throwing the handle 56 over into the "loud" position, the outer horn is closed and the inner horn is fully opened to the sound waves, with the result that we get a stronger 5 reproduction.

In Figs. 10 and 11, the inner horns 38 and 10 50 may, if desired, be provided with lateral openings similar to the inner horns shown in Fig. 1, 6 and 7. In that case, the sound waves would always issue out of both horns, but valve V or V' would operate just the same to control the relative proportion of sound waves passing through the horns.

It is clear that the amplifiers shown in 15 Figs. 8 to 13, inclusive, may be used in radio loudspeakers by simply inserting them in the base of the instrument, as in Fig. 6, or they may be embodied in phonograph cabinets similar to the arrangement shown in 20 Fig. 7. In the latter case, the tone-controlling valve could be operated from the side of the cabinet by simply attaching a rod to the end of handle 45 or 56, as will be readily understood. Also, it is apparent that the 25 constructions of Figs. 8-13 may be enclosed in a box like that shown in Fig. 1. In that case, the extension 39 (Fig. 8) or 48 (Fig. 11) is connected to the arm 15 of Fig. 1.

Attention is called to the fact that the 30 tone-controlling device of my invention, whether employed at the mouth of the inner horn (as in Figs. 1, 6 and 7), or at the base of the horns (as shown in Figs. 8 to 13), is not a choking or throttling damper; 35 rather is it a valve for shifting or deflecting the passage of sound waves through both horns simultaneously in varying proportions. Consequently, my controlling mechanism does not produce the "choky" 40 effect of the horn dampers previously employed.

It will be apparent from the foregoing 45 explanation that my new sound-amplifier with its sound chambers of different tone effects gives better reproduction than prior devices employing a single horn or chamber. Furthermore, by means of the tone 50 valve or shutter, the amplifying action of my device is readily controlled by the operator to produce any tone effect within the 55 limits of the instrument. In the matter of construction, my new amplifier is remarkably simple and easy to make, besides being compact in the arrangement of parts.

The amplifier of my invention possesses 60 special advantages for radio reception, where broadcast programs vary from the reporting of sporting events to the rendition of vocal or instrumental solos. An amplifier adapted to give the best reproduction of speech does not usually give the best results in reproducing music or song, and vice versa. For instance, it has been found that 65 in reproducing announcements of sporting events in a large hall, a loudspeaker with a

high resonant pitch is more satisfactory than one emitting low rumbling tones, which lack clearness. On the other hand, a piano solo is best reproduced with an amplifier having mellow tonal characteristics. Now, my new amplifier may be so regulated in its tone reproduction as to give the best results in the reproduction of any kind of broadcasting. In other words, the amplifier of my invention embodies a plurality of amplifiers in a single instrument. 70 75

Although I have herein shown and described certain specific constructions, it is clear that the broad idea of my invention may be mechanically embodied in other 80 ways. The size, shape and material of the horns or sound chambers may be varied in accordance with the particular tone effects desired to be produced. Also, the number and relative arrangement of the horns may 85 be varied to suit particular circumstances or to effect certain results. While I have spoken of the inner horns as the resonant sound chambers and of the outer horns as the more mellow sound chambers, it is obvious 90

that the outer horns may be constructed to give more resonance than the inner horns. The difference in tone effects between the various sound chambers may be brought about not only by the use of different materials, as already mentioned, but by variations in size and shape of the horns, even with the same material. Nor is it necessary that the horns are nested, as shown, although that arrangement is desirable from 95 a practical standpoint on account of the resulting compactness. When I refer to nested horns or sound chambers in the description and claims, I do not mean that they shall be concentrically mounted, but 100

I include any arrangement in which the smaller chamber is within the casing of the larger chamber. In the broader aspect of my invention, the inner horn may be regarded as a wall within the casing formed 110 by the walls of the larger chamber and dividing said casing into two sound chambers of different tonal characteristics. It is preferable to support the horns independently of each other, for any direct connection between the horns, such as spacing rods, would cause the vibrations of one horn to be communicated to the other, thereby injuring the quality of reproduction. The walls of the sound chambers should be 115 120 smooth and rigid for the best results.

As far as I am aware, I am the first to 125 pluralify sound chambers constructed to produce different tone effects, and having means for controlling the resultant tone quality by regulating the relative proportion of sound waves passing simultaneously through the amplifying chambers. I, therefore, claim this idea in a fundamental way.

Since in the appended claims I claim my 130

invention broadly and also specifically claim the construction of Figs. 1-5, I do not herein make any specific claims to the constructions shown in Figs. 8-13, which 5 I reserve the right to claim in a divisional application.

I claim as my invention:

1. A sound-amplifier comprising a pair of nested diverging sound chambers, the 10 walls of one of said chambers being of a material adapted to give a resonant reproduction and the walls of the other chamber being of a material adapted to give a relatively softer or more mellow reproduction, the inner chamber having sound openings for laterally communicating with the outer chamber, and means for controlling the relative proportion of sound waves passing through said openings.
2. A sound-amplifier comprising a plurality of nested sound chambers constructed to produce different tone effects, and means for simultaneously controlling the acoustic effects of the individual chambers, whereby 25 the resultant sound reproduction combines the tonal characteristics of said chambers in varying degrees.
3. A sound-amplifier comprising a pair of nested diverging sound chambers, the 30 walls of the inner chamber being of metal and the walls of the surrounding outer chamber being of non-metallic material, and means for controlling the relative proportion of sound waves issuing simultaneously 35 out of said chambers.
4. In a sound-amplifier, a pair of nested diverging sound chambers open to the air at their outer ends, the walls of the inner chamber being of a material adapted to give 40 a resonant reproduction, the walls of the surrounding outer chamber being of a material adapted to give a relatively softer or more mellow reproduction, means for connecting said chambers with a source of sound, and 45 an adjustable valve for controlling the relative proportion of sound waves issuing simultaneously out of said chambers.
5. In a sound-amplifier, the combination of a horn adapted to be connected at its 50 inner end with a source of sound and constructed of a material adapted to give a resonant reproduction, outwardly diverging walls surrounding said horn and arranged to form around the same a sound chamber 55 open at its outer end, said walls being of a material adapted to give a relatively softer or more mellow reproduction, sound passages leading into said surrounding chamber, and means for controlling said passages to vary the relative proportion of 60 sound waves issuing simultaneously out of said horn and out of said chamber.
6. In a sound-amplifier, a pair of nested diverging sound chambers open to the air 65 at their outer ends and constructed to pro-

duce different tone effects, means for connecting said chambers with a source of sound, and a valve for controlling the relative proportion of sound waves passing simultaneously through said chambers.

7. In a sound-amplifier, a casting comprising a main tubular section provided between its ends with a surrounding flange, one end of said tubular section being adapted to be connected with a source of sound, a horn having its inner end fastened to the other end of said tubular section, diverging walls arranged to form a sound chamber around said horn and secured at their inner ends to said flange, the axis of said tubular section being substantially coincident with the axes of said horn and said surrounding chamber.

8. As a new article of manufacture for use in sound amplifiers, a casting comprising a main tubular section open at both ends, and an outwardly flaring flange surrounding said main section between its ends and radially spaced therefrom, for the purposes specified.

9. In a sound-amplifier, the combination of a horn open at its outer end and adapted to be connected at its inner end with a source of sound, outwardly diverging walls surrounding said horn and arranged to form around the same a sound chamber open at its outer end, said horn having sound openings for laterally communicating with said chamber, whereby the sound waves entering the horn pass into the outer air partly through the horn and partly through said surrounding chamber, and means for regulating the relative proportion of sound waves issuing simultaneously out of said horn and out of said chamber.

10. In a sound-amplifier, the combination of a metal horn open at its outer end and adapted to be connected at its inner end with a source of sound, non-metallic walls surrounding said horn and arranged to form around the same a diverging sound chamber open at its outer end, said horn having sound openings for laterally communicating with said chamber, whereby the sound waves entering the horn pass into the outer air partly through the horn and partly through said surrounding chamber, and an adjustable shutter at the mouth of said horn for controlling the proportion of sound waves issuing out of the mouth of said horn and out of said surrounding chamber.

11. In a sound-amplifier, a pair of nested horns adapted to be connected with a source of sound, and an adjustable valve for controlling the relative proportion of sound waves issuing simultaneously out of both horns.

12. In a sound-amplifier, a pair of nested horns adapted to be connected with a source of sound, the inner horn having sound openings for laterally communicating with the

- outer horn, whereby the sound waves entering the inner horn pass into the outer air partly through the inner horn and partly through the outer horn, and a manually adjustable valve for controlling the relative proportion of sound waves issuing simultaneously out of both horns.
13. In a sound-amplifier, the combination with a pair of nested horns adapted to be connected with a source of sound, of a rotatable valve for regulating the passage of sound waves simultaneously through both horns.
14. In a sound-amplifier, the combination with a pair of nested horns adapted to be connected with a source of sound, of manually operable means for regulating the passage of sound waves simultaneously through both horns.
15. In a sound-amplifier, a pair of nested horns open at their outer ends and adapted to be connected with a source of sound, a frame at the mouth of the inner horn and having one or more sound openings, and a rotary disk mounted in said frame for controlling said openings to vary the relative proportion of sound waves issuing out of said horns.
16. A sound-amplifier comprising a pair of nested diverging sound chambers open to the air at their front or outer ends, a sound-conveying tube supported outside of said chambers and extending lengthwise thereof from near the front ends of said chambers toward the inner ends thereof, the outer end of said tube being adapted to be connected with a source of sound, and a member for acoustically connecting the rear or inner end of said tube with the inner end of said chambers.
17. A sound-amplifier comprising, walls or partitions arranged to form a diverging sound chamber open to the air, a substantially U-shaped sound-conveying member arranged partly within said chamber and partly without, said member tapering from its smaller sound-inlet end to its larger sound-outlet end, the mouth or larger end of said member terminating at or near the mouth of said chamber, and means for emitting sound waves from said member into said sound chamber.
18. A sound-amplifier comprising walls arranged to form a diverging sound chamber open at its front or larger end, a horn supported lengthwise within said chamber, a sound conduit at the inner ends of said horn and chamber, and a sound-conveying tube mounted outside of said chamber so as to extend from the front toward the rear thereof, the outer end of said tube being adapted to be connected with a source of sound and the inner end of said tube being connected to said sound conduit.
19. A sound-amplifier comprising, walls arranged to form a diverging sound chamber open at its front or larger end, a horn supported lengthwise within said chamber, a sound conduit at the inner ends of said horn and chamber, and a sound-conveying tube mounted outside of said chamber so as to extend from the front toward the rear thereof, the outer end of said tube being adapted to be connected with a source of sound and the inner end of said tube being connected to said sound conduit.
20. A sound-amplifier comprising a box or cabinet having an outer opening at the front, walls arranged in said cabinet to form a sound chamber diverging toward said outer opening, a horn supported lengthwise within said chamber and having sound openings for laterally communicating with said chamber, a sound-conveying tube mounted in said cabinet outside of said sound chamber and extending from near said front opening toward the rear of the cabinet, the outer end of said tube being adapted to be connected with a sound-producing device from outside the cabinet, means for connecting the inner end of said tube with the inner end of said horn, an open frame or grille secured over said outer opening of the cabinet, and an adjustable valve or shutter carried by said frame over the mouth of said horn to control the relative proportion of sound waves issuing out of said chamber and said horn.
21. A sound-amplifier comprising walls arranged to form a diverging sound chamber open at its front or larger end, a horn supported lengthwise within said chamber, a sound conduit at the inner ends of said horn and chamber, and a sound-conveying tube mounted outside of said chamber, said tube comprising a section extending substantially parallel with said horn from near the outer opening of said chamber toward the rear thereof and a second section extending transversely of said horn at the rear of said chamber for connection with said sound conduit, the outer end of said tube being adapted to be connected with a source of sound.
22. A sound-amplifier comprising walls arranged to form a diverging sound chamber open at its front or larger end, a horn supported lengthwise within said chamber and terminating substantially at the mouth of said chamber, said horn having sound openings for laterally communicating with said chamber, a tapering sound-conveying tube mounted outside of said sound chamber and arranged substantially parallel with and laterally of said horn, the smaller end of said tube being adapted to receive or be connected with a sound-producing device, and a substantially U-shaped tubular member for

- connecting the larger end of said tube with the inner end of said horn.
23. A sound-amplifier comprising a box or cabinet with an outer opening, walls arranged within said cabinet to form a sound chamber diverging toward said outer opening and terminating substantially at said opening, a horn supported lengthwise within said chamber and terminating substantially at the mouth of said chamber, said horn having sound openings for laterally communicating with said chamber, a tapering sound-conveying tube mounted in said cabinet outside of said sound chamber and arranged substantially parallel with and laterally of said horn, the smaller end of said tube being adapted to receive or be connected with a sound-producing device from outside the cabinet, a substantially U-shaped tubular member for connecting the larger end of said tube with the inner end of said horn, an open frame or grille secured over the outer opening of the cabinet, and an adjustable valve or shutter carried by said frame over the mouth of said horn for regulating the proportion of sound waves passing through said lateral openings in the horn and through the mouth of the horn.
24. In a sound-amplifier, a pair of nested horns adapted to be connected with a source of sound, the inner horn having openings for laterally communicating with the outer horn, and a device for controlling the proportion of sound waves issuing simultaneously through said lateral openings and through the mouth of the inner horn.
25. In a sound amplifier having a pair of nested horns or sound chambers, a combined sound conduit and support for said horns comprising a tubular section open at both ends for the passage of sound, and an outwardly flaring flange around said tubular section and radially spaced therefrom, said flange being adapted to support the inner end of the outer horn and one end of said tubular section being adapted to support the inner end of the inner horn.
26. A sound-amplifier comprising a pair of nested diverging sound chambers, the walls of one of said chambers being of a material adapted to give a resonant reproduction and the walls of the other chamber being of a material adapted to give a relatively softer or more mellow reproduction, and means for controlling the relative proportion of sound waves issuing simultaneously out of said chambers.
27. A sound amplifier comprising walls arranged to form a diverging casing, a wall mounted within said casing to divide the same into two outwardly diverging sound chambers of different tonal characteristics, said chambers being open at the larger outer ends for the emission of sound, means for connecting the inner ends of said chambers with a source of sound, and means for controlling the relative proportion of sound waves passing simultaneously through said chambers.

ADOLPH A. THOMAS.

Certificate of Correction.

It is hereby certified that in Letters Patent No. 1,481,634, granted January 22, 1924, upon the application of Adolph A. Thomas, of New York, N. Y., for an improvement in "Sound Amplifiers," an error appears in the printed specification requiring correction as follows: Page 5, after line 122 insert the words *produce a sound amplifier comprising a*; and that the said Letters Patent should be read with this correction therein that the same may conform to the record of the case in the Patent Office.

Signed and sealed this 5th day of August, A. D. 1924.

[SEAL.]

WM. A. KINNAN,
Acting Commissioner of Patents.
